UNITED STATES PATENT OFFICE

AUSTIN B. BELGARD, OF CHICAGO, ILLINOIS, ASSIGNOR TO BELGARD-SPERO, INC.,
A CORPORATION OF DELAWARE

DESIGN FOR A TEMPLE FOR SPECTACLES

Application filed October 29, 1932. Serial No. 45,629. Term of patent 7 years.

To all whom it may concern:

Be it known that I, AUSTIN B. BELGARD, a citizen of the United States, residing at Chicago, in the county of Cook, State of Illinois, have invented a new, original, and ornamental Design for Temples for Spectacles, of which the following is a specification, reference being had to the accompanying drawing, forming a part thereof, in which:

Fig. 1 is a perspective view of a temple for spectacles, showing my new design, and
Fig. 2 is a side elevation of the temple.

I claim:

The ornamental design for a temple for spectacles, as shown.

AUSTIN B. BELGARD.
